REGULATING TRANSFORMER

Georg Leischner, Berlin-Schmöckwitz, Germany,
assignor to N. V. Machinerie-en Apparaten
Fabrieken "Meat", Utrecht, Netherlands

Application July 9, 1935, Serial No. 30,570
In Germany July 24, 1934

8 Claims. (CL. 171—119)

The present invention relates to a regulating transformer. One use of such a transformer consists, e. g. in maintaining the constancy of the potential of an alternating current net, notwithstanding varying load or fluctuations in feed potential. Another use is the generation of a variable potential, for instance, for feeding the motors of electric locomotives.

For the purpose of regulating alternating potentials, generally transformers are employed, in which one coil is provided with taps being connected with contacts, with the result that different lengths of this coil can be interpolated. When passing from one contact to the next following one, the electric current must ordinarily be interrupted for a short period. If such an interruption is to be avoided, the connection with the next succeeding contact must be made before that with the preceding one is broken, in connection with which that part of the coil, being situated between the two contacts, is short-circuited. Powerful short-circuit currents are produced thereby in this part of the coil, causing an inadmissible heating of the coils, the interruption of which produces destructive arcs.

The present invention relates to a regulating transformer in which these defects have been avoided by causing the iron core to comprise a plurality of partial cores and causing the regulating coil to so contact with a contact slide that, when two adjacent contacts are short-circuited, the short-circuited portion encompasses merely one partial core and the flux, which would otherwise pass through this partial core, is forced off on to the other partial cores.

Further advantages, characterizing the present invention, will appear more fully from the following description, particularly when considered in conjunction with the accompanying drawings, which are forming part thereof.

Fig. 1 is a diagrammatic side elevation of a part of a regulating transformer in accordance with the present invention.

Fig. 2 represents a diagrammatic plan view of the identical part.

Fig. 3 illustrates an arrangement with five partial cores and a star-shaped contact slide.

Fig. 4 is a side elevation of a form of performance of a regulating transformer in accordance with the present invention.

Fig. 5 is a cross-sectional view along the line 5—5 of Fig. 4.

Fig. 6 is a side elevation of a further form of performance in section along the line 6—6 of Fig. 7.

Fig. 7 is a cross-sectional view along the line 7—7 of Fig. 6.

Fig. 8 represents an arrangement in accordance with Fig. 5, in which taps on the regulating coil are made to pass through between the partial cores.

Fig. 9 details an arrangement corresponding to Fig. 7, in which taps on the regulating coil are made to pass through between the partial cores.

In the regulating transformer, represented in Figs. 1 and 2 only partly and diagrammatically, the iron core may be of any desired shape, such as is known in the art in connection with transformers. From these known forms the core of the regulating transformer in accordance with the present invention differs, however, in so far as the portion, encompassed by the regulating coil 10, is sub-divided into two or more partial cores, i. e. in the case of Figs. 1 and 2, into two partial cores a_1 and a_2 , being separated by the air gap 11. Within this air gap 11 the contact slide 12 is so disposed, that it allows of being displaced in a longitudinal direction of the core and that the contact pieces 13, attached to the contact slide 12, are made to establish contact on the inner face of the regulating coil alternately with the one or the other winding.

If the contact slide is made to occupy the position as represented in Fig. 1, in which both contacts 13 are touching the regulating coil, the one winding half, encompassing the partial core a_1 , will then be short-circuited and the flux will be forced out therefrom. If the contact slide is further displaced so as to establish contact with the next winding, the winding-half, encompassing the partial core a_2 , will be short-circuited and the flux forced out therefrom and so on, until the contact slide has covered the whole of the path.

It is, however, advantageous, to split up the core into more than two partial cores, e. g. into four, and to cause the contact slide to be cross-shaped, as shown in Fig. 5. In connection with more than four partial cores the contact slide should be star-shaped, as shown in Fig. 3. The width of the contact pieces 13 in the direction of the core, must then always be so selected, that always only two contacts touch the regulating coil, because otherwise the flux will be forced out from more than one partial core.

In the Figs. 4 and 5 one form of performance of a regulating transformer in accordance with the present invention has been represented. The iron core is made to carry on one of the limbs the primary coil 15 and on its other limb the regulating coil 16. The core encompassed by the regu-

lating coil consists of four partial cores, a_1 , a_2 , a_3 , and a_4 . In the cross-shaped air-gap between these four partial cores the contact slide 17 is slidably disposed in the direction of the longitudinal axis 5 of the regulating coil. This contact slide 17 touches the regulating coil 16 inwardly by means of its four contact pieces 18, 19, 20, and 21. In order to represent the position of the contact slide, Fig. 4 is made to show the arrangement in 10 section at the point, where the contact slide is situated. It will be seen without any difficulty, that in the position of the contact slide indicated in the drawings, the contact pieces 18 and 21 are establishing contact with the regulating coil, where- 15 by a short-circuit, encompassing the limb a_4 , will be produced. This will cause the flux, passing through the limb a_4 at uniform distribution, to be forced off to the limbs a_1 , a_2 , and a_3 , so that in the short-circuit, encompassing the limb a_4 , no short- 20 circuit currents, endangering the arrangement, will be produced. If the contact slide is moved further in an upward direction, the contact between the contact piece 21 and the regulating coil 25 will be broken in the first instance and, in consequence of a further movement, the contact between the contact piece 18 and the regulating coil will be closed. In this position the partial limb a_1 will then be encompassed by a short-circuit and the flux will be forced away from this limb.

30 For the purpose of shifting the contact slide, a rack 22, in which a toothed wheel 23, actuated by means of a crank 24, is made to engage, is passed through the limb of the iron core in an axial direction. A sliding contact 25 is made to serve as 35 current feed to the contact slide. The variable potential produced can be taken off between one of the binding posts 26 and the binding post 27. It is a matter of course, that the arrangement may also be used as auto-transformer and that the primary potential can be connected with the two binding posts. The primary coil 15 can, in this 40 instance, be dispensed with.

The contact slide can also be so disposed, that it establishes contact with the outer face of the 45 regulating coil instead of the inner face. In this case the magnetic flux return conductors require to be sub-divided and the separate contact pieces of the contact slide to be passed through between the former.

50 An arrangement of this kind is shown in Figs. 6 and 7. The iron core is so composed of four bi-limbed iron cores, that the four limbs a_1 , a_2 , a_3 , and a_4 are forming a whole being encompassed by the primary coil 28 and the secondary winding 29. Outside of these two windings the limbs 55 b_1 , b_2 , b_3 , and b_4 have been annularly disposed. Around the limbs b_1 – b_4 a ring 30, serving as contact slide, has been provided and is adapted to be displaced in the direction of the axis of symmetry 60 of the arrangement. From this ring four contact arms 31, 32, 33, and 34, provided with contact pieces 35, 36, 37, and 38, are made to pass through between the cores b_1 to b_4 , said contact pieces being made to contact with the coil 29. In the position 65 of the contact slide 30 as indicated in Fig. 6, the contact arms 36 and 37 are made to establish contact with the regulating coil. This will cause a short-circuit, encompassing the limb b_3 , to be produced and the flux, passing through this limb 70 at uniform distribution, will be suppressed. In conformity therewith, the flux in the limbs b_1 , b_2 , and b_4 will be increased. Four screw spindles 39, 40, 41, and 42 may be made to serve for displacing the contact slide 30.

75 Instead of providing the contact slide with con-

tact arms which are made to pass through the cores, it will be possible to provide in the forms of the invention as shown in Figs. 1 to 5, as well as in the form of the invention as shown in Figs. 6 to 7, also on the regulating coil tappings passing 5 through between the partial cores and establishing contact with the contact pieces of the contact slide, as shown in Figs. 8 and 9. The contact slide is also adapted, apart from the displacement in direction of the axis of the regulating coil, to 10 describe an eccentric motion round the regulating coil.

It is, of course, understood, that in all the arrangements described, the direction of the energy 15 may be reversed and that the regulating coils may be connected with the source of supply as primary coils, and the fixed coils with the point of consumption as secondary coils.

I wish it distinctly to be understood, that I do not desire my invention to be limited to the exact 20 details of the construction shown and described, for obvious modifications will occur to any person skilled in the art.

What I claim, is:

1. A regulating transformer, comprising an 25 iron core, a regulating coil, a contact slide and contact pieces, the part, encompassed by the regulating coil, consisting of a plurality of partial cores, the contact slide being moveably disposed between the partial cores, the contact 30 pieces on the contact slide being so arranged, that they establish contact with the inside of the regulating coil and that the short-circuit, produced by the contact of two points of the regulating coil, 35 encompasses one partial core.

2. A regulating transformer, comprising an iron core, a regulating coil, a contact slide and contact pieces, the part of the iron core, encompassed by the regulating coil, being made to consist of a plurality of partial cores annularly disposed, the star-shaped contact slide being moveably disposed between the partial cores, the contact 40 pieces on the contact slide being so disposed, that they establish contact with the regulating coil on the inside and that the short-circuit, produced by the contact of two points of the regulating coil, 45 encompasses one partial core.

3. A regulating transformer, comprising an iron core, a regulating coil, a contact slide and contact pieces, the part of the iron core encompassed by the regulating coil being made to consist of four partial cores, the cross-shaped contact slide being moveably disposed between the partial cores, the contact pieces on the contact 50 slide being so disposed, that they establish contact with the regulating coil on the inside and that the short-circuit, produced by the contact of two points of the regulating coil, 55 encompasses one partial core.

4. A regulating transformer, comprising an iron core, a regulating coil, a contact slide and contact pieces, the part of the iron core encompassed by the regulating coil consisting of a plurality of partial cores, the contact slide being moveably disposed between the partial cores, the contact pieces on the contact slide being so disposed, that they establish contact with the regulating coil on the inside and that the short-circuit, produced by the contact of two contact 60 pieces connected with the regulating coil, 65 encompasses one partial core.

5. Regulating transformer, comprising an iron core, a regulating coil, a contact slide and contact pieces, the part of the iron core, situated 70

- 5 outside the regulating coil, consisting of a plurality of partial cores, the contact slide outside the partial cores being moveably disposed, the contact pieces being so disposed on the contact slide that, passing through between the partial cores, they establish contact with the outside of the regulating coil and that the short-circuit, produced by the contact of two points of the regulating coil, encompasses one partial core.
- 10 6. Regulating transformer, comprising an iron core, a regulating coil, a contact slide and contact pieces, the part of the iron core, situated outside the regulating coil, consisting of a plurality of annularly disposed partial cores, the contact slide outside the partial cores being moveably disposed, the contact pieces on the contact slide being so disposed, that they are made to pass through between the partial cores and establish contact with the regulating coil on the outside and that the short-circuit, produced by the contact of two points of the regulating coil, encompasses one partial core.
- 15 7. Regulating transformer, comprising an iron core, a regulating coil, a contact slide and contact pieces, the part of the iron core situated

5 outside the regulating coil consisting of a plurality of partial cores, the contact slide outside the partial cores being moveably disposed, the contact pieces being so disposed on the contact slide, that they establish contact with the contact pieces, connected with the regulating coil, from the outside and that the short-circuit, produced by the contact of two contact pieces connected with the regulating coil, encompasses one partial core.

10 8. A regulating transformer comprising a plurality of partial cores, over which the power flux generated by a transformer is distributed, a regulating coil and a contact slide, at least one of the cores carrying the regulating coil, the contact slide engaging between the partial cores provided with at least two electrically connected contacts which contact with the regulating coil encompassing the core at two diametrically opposite points, in such manner that the thereby resulting short circuit encompasses only one of the cores partially traversed by the main current flux.

GEORG LEISCHNER. 25
